United States Patent Office

Des. 224,692
Patented Aug. 29, 1972

224,692

PACKAGE DISPENSING CONTAINER

Laverne E. Gray, Dallas, Tex., assignor to Lone Star
Container Corporation, Dallas, Tex.

Filed Dec. 21, 1970, Ser. No. 26,588

Term of patent 14 years

Int. Cl. D9—03

U.S. Cl. D52—2

FIG. 1

FIG. 2

FIG. 3

FIG. 4

FIG. 5

FIG. 6

FIG. 1 is a perspective view of the "package dispensing container" showing my new design; and

FIG. 2 is a right side elevational view thereof; and
 FIG. 3 is a front elevational view thereof; and
 FIG. 4 is a rear elevational view thereof; and
 FIG. 5 is a top plan view thereof; and
 FIG. 6 is a bottom plan view thereof.

I claim:

The ornamental design for a package dispensing container, substantially as shown.
